SCREW DRIVER AND SOCKET WRENCH
ATTACHMENT

Thomas Miller, Brooklyn, N. Y.

Application September 25, 1936, Serial No. 102,467

5 Claims. (Cl. 81—121)

This invention relates to socket wrenches operated by a screw driver and an object is to provide a simple duplex clip mounted on the socket wrench and adapted to grip the reduced shank portion above the bit of the screw driver.

Another object of this invention is to provide a socket wrench having integrally secured thereto a duplex elastic resilient spring clip having two arms disposed longitudinally of the socket 10 and designed for resiliently gripping the shank portion above the bit of a screw driver having sideways extending shoulders whereby the arms interlock with said shank portion directly above said shoulders and afford sufficient resistance 15 against disengagement while at the same time a comparatively slight push or pull applied centrally to the screw driver through the medium of its handle is sufficient to overcome the resistance afforded by the spring arms so that the screw 20 driver may be intentionally removed or replaced with comparative ease.

Another object of this invention is to provide modified engagement means whereby the duplex clip is mounted in the socket wrench and is adapted 25 to grip the end walls of the bit of a screw driver.

With the above and other objects in view, the invention will be hereinafter more particularly described, and the combination and arrangement 30 of parts will be shown in the accompanying drawing and pointed out in the claims which form part of this specification.

Reference will now be had to the drawing, wherein like numerals of reference designate corresponding parts throughout the several views, in which:

Figure 1 is a front elevation of a screw driver mounted in a socket wrench body and held fast by two resilient arms engaging the shoulders of 40 the bit of the screw driver.

Figure 2 is a top view of the assembled socket wrench body and resilient holding means.

Figure 3 is a bottom view of the socket wrench body.

Figure 4 is a front elevation of a modified socket wrench body and resilient holding means in assembled relation.

Figure 5 is a front elevation of the modified socket wrench body.

Figure 6 is a cross-sectional view of a modified socket wrench body and holding means for screw drivers having parallel end walls.

Figure 7 is a front elevation of an adapter used for coupling a screw driver and a socket wrench body of usual construction.

In the illustrated embodiment of the invention shown in Figures 1 to 3 inclusive, the numeral 10 indicates the body of a socket wrench which preferably has an upper end 11 of circular form and of smaller diameter than the lower end. The 5 upper end has a rectangular and downwardly tapering opening 12 designed to permit entrance of the tapering bit of a screw driver.

Figure 1 shows the bit 14 of a screw driver 13 inserted in the opening 12. The bit 14 is defined 10 from the shank 15 by two shoulders 16 which project out from the shank. The width of the bit at the shoulders is greater than that at its lower end 17 and when looking at the front face 15 of the screw driver, the end walls of the bit 14 appear slightly tapering with the smallest end of the taper directed outward.

As shown in Figure 2, the lengthwise sides of the rectangular opening 12 taper considerably to correspond with the considerably tapering front 20 and rear faces of the bit as is usual in screw driver construction.

For the purpose of securing the screw driver 13 and the socket wrench body 10 in unitary relation, I have provided a resilient holding means 18 having a tubular body portion 19 designed to frictionally embrace the upper end 11 of the body 10. The tubular body portion 19 is slit at 25 20 in a longitudinal direction and the two edges at the slit are slightly curved outwardly. Projecting upwardly from the tubular body 19 are two arms 21 which are resilient in action and have inwardly turned ends or terminals 22. The arms 21 slidably operate on opposite end walls of the bit 14 and interlock with the shank 15 above 30 the shoulders 16. The arms 21 have at the free 35 and inwardly turned ends 22 outwardly projecting extensions 23 which facilitate the insertion or removal of a screw driver from the opening 12.

It is to be noted that the tubular body portion 19 of the resilient holding means 18 is designed 40 so as to be frictionally slid over the reduced upper end 11 of the socket wrench body 10 and so that it may be removed therefrom at will.

Figure 4 shows a modified socket wrench body 45 25 and a modified resilient holding means 26. The modified socket wrench body 25 has a reduced upper end 27 and a circular groove 28, best shown in Figure 5. The spring holding means 26 is preferably made from a flat annular 50 body 29 which is split at 30 and has longitudinally extending spring arms 31, similar to the spring arms 21. The extensions 32 of the arms 31 may be further extended and made in corrugated form, as shown at 33 in Figure 4, so that 55

the shoulders of a variety of screw drivers 13 may be used, having bits of different lengths, the shoulders of which may be easily gripped by an upper or a lower set of the corrugations on said arms. The groove 28 is used for receiving and clamping the flat annular body 29 therein.

Figure 6 shows a modified socket wrench body 35 which may have a reduced upper end 36 and a duplex clip or resilient frictional holding means 38 mounted in the body. The body 35 has an opening 37 designed for receiving and securing a screw driver having parallel end walls.

Figure 7 shows an adapter 40 for coupling a screw driver having shoulders and a socket wrench body of usual construction, that is, a body 41 having an upper hexagonal opening 42 for a handle (not shown) and a lower hexagonal opening 43 for receiving a hexagonal nut. The adapter 40 has a lower extension or handle 44 with the usual spring-pressed ball 45 for frictional engagement with the opening 42 in the body 41. The adapter body 40 has an opening 46 in its upper end to receive a screw driver (not shown). Mounted on the body 40 is a circular spring clip 47 having an upper extension 48 and an inwardly turned end 49 which is designed for engagement with the shoulders of the shank of a screw driver similar to that shown in Figure 1.

It is to be noted that the spring holding means 30 or clips shown herewith may have one or more arms for securing a screw driver and these clips may be permanently secured to the socket wrench body or may frictionally be disengaged therefrom.

I claim:

3.5 1. A socket wrench attachment for screw drivers having a tapering bit portion wider than the shank and forming shoulders, comprising a socket wrench having a tapering opening designed to receive the tapering bit of said screw driver, spring means comprising two arms held by said socket wrench longitudinally of said opening, said arms being disposed relative to said opening so as to face the shoulders of said screw driver, said arms being of a length to grip the screw driver shank directly above said shoulders and attach the socket wrench and said screw driver in unitary relation by positive interlocking engagement.

2. A socket wrench attachment for screw drivers having a tapering bit portion wider than the shank and forming shoulders, comprising a member having a tapering opening designed to receive the tapering bit of said screw driver, spring means comprising two resilient arms held by said member longitudinally of said opening, each of said arms being formed with a curved terminal adapted to spring over said shoulders, said arms

being disposed relative to said opening so as to face the shoulders of said screw driver, said arms being of a length to grip the screw driver shank directly above said shoulders and attach said member and said screw driver in unitary relation by positive interlocking engagement, said member having an extension at its lower end, and said extension having spring-pressed means for attachment to a socket wrench.

3. A socket wrench attachment for screw drivers having a tapering bit portion wider than the shank and forming shoulders, comprising a socket wrench having a tapering opening designed to receive the tapering bit of said screw driver, spring means comprising two resilient arms held by said socket wrench longitudinally of said opening, each of said arms being formed with one or more curved terminals respectively adapted to spring over said shoulders, said arms being disposed relative to said opening so as to face the shoulders of said screw driver, said arms being of a length to grip the screw driver shank directly above said shoulders and attach the socket wrench and said screw driver in unitary relation by positive interlocking engagement.

4. In a screw driver and socket wrench combination of the class described, comprising a socket wrench member having a tapering opening to receive the bit of a screw driver, a screw driver member having shoulders extending sideways above the bit, a connecting spring member having an annular body portion at one end designed to interlock with said socket wrench, said socket wrench body having a reduced end and an annular groove in the external surface of said reduced end, said groove being adapted to receive said annular body portion of said spring, said spring having arms of a length to grip the screw driver shank directly above said shoulders and attach the socket wrench and said screw driver in unitary relation by positive interlocking engagement.

5. A socket wrench attachment for screw drivers having a tapering bit portion wider than the shank and forming shoulders, comprising a socket having a tapering opening designed to receive the tapering bit of said screw driver, spring means held by said socket longitudinally of said opening, said spring means being disposed relative to said opening so as to grip the shoulders of said screw driver, said spring means being of a length to grip the screw driver directly above said shoulders and attach the socket and said screw driver in unitary relation by positive interlocking engagement.

THOMAS MILLER.
